United States Patent Office

Des. 222,594

Patented Nov. 9, 1971

222,594

TURNS COUNTING DIAL

Paul R. Trautmann, Whittier, Roger G. Igon, Santa Monica, and Ronald E. Loosen, Woodland Hills, Calif., assignors to Spectrol Electronics Corporation, Industry, Calif.

Filed Feb. 24, 1970, Ser. No. 21,568

Term of patent 14 years

Int. Cl. D10—04

U.S. Cl. D52—6

FIG. II

FIG. I

FIG. III

FIG. 1 is a perspective view of a turns counting dial embodying our new design;

FIG. 2 is a side elevational view thereof; and

FIG. 3 is a top plan view thereof.

The back side of the design is substantially plain and unornamented.

The stippling in the drawing is utilized to illustrate contrast.

We claim:

The ornamental design for a turns counting dial, substantially as shown and described.
